ELECTRIC CONTACT PLUG

Charles L. Hile, Louisville, Ky., assignor of one-half to William Ruedeman, Louisville, Ky.

Application April 19, 1935, Serial No. 17,343

2 Claims. (Cl. 173—332)

This invention relates to certain new and useful improvements in electric contact plugs.

The primary object of the invention is to provide an electric contact plug of the type employed in connection with electric sad irons, toasters, heaters and the like for attachment to terminals for the conduction of electricity.

In attachment plugs of the foregoing character, two contacts are usually employed and are of the spring type for engagement with two terminals and the interior of the plug casing becomes highly heated and hastens disintegration of the casing body and wear on the contacts. It is therefore an important object of this invention to provide for a thorough ventilation of the plug by disposing the conductor wires in spaced relation at their points of entry into the plug casing and to utilize the usual resilient plug pulling device as an air ventilating passage for the circulation of air into and through the plug casing, and for anchoring the conductor wires.

A still further object of the invention is to provide a contact plug of the foregoing character wherein the electric wires that are attached to the contacts are spaced from each other within the plug casing and pass outwardly of the casing at spaced points respectively opposite the longitudinal axis of the casing so that liability of the wires touching each other within the casing is eliminated.

With the above and other objects in view that will become apparent as the nature of the invention is better understood, the same consists in the novel form, combination and arrangement of parts hereinafter more fully described, and then claimed.

In the drawing:—

Figure 1 is a side elevational view of an electric contact plug constructed in accordance with the present invention, showing the conductor wires separated at their points of passage from the plug casing;

Figure 2 is a plan view of the plug with one casing section removed and showing the spaced relation of the spaced conductor wires within the casing and the unobstructed air passage from the casing through the resilient plug pulling device;

Figure 3 is a side edge elevational view of the plug;

Figure 4 is an outer end elevational view of the resilient plug pulling device;

Figure 5 is a detail sectional view taken on line 55 5—5 of Figure 3;

Figure 6 is a detail sectional view taken on line 6—6 of Figure 3; and

Figure 7 is a plan view of one of the casing sections with the contacts removed and showing the lateral passages for the conductor wires. 5

Referring more in detail to the accompanying drawing, there is illustrated an electric contact plug of the conventional exterior configuration and comprising sections 10 of identical construction mating to form the casing and secured together by the usual transversely extending counter-sunk nut and bolt combinations 11.

Each casing section 10 as shown in Figure 7 has a raised central longitudinally extending rib 12 providing lateral grooves 13 for the reception of the usual contacts 14 and each groove 13 has cross ribs 15 rising from the bottom walls thereof to space the contacts 14 from the walls of the casing 10. The ribs 12 have openings 16 therein through which the bolts 11 pass. 20

The inner end of each casing section 10 is provided with a semi-circular channel 17 with the two channel sections mating to form a circular channel for the reception of one end of the resilient plug puller. The semi-circular channels 17 are spaced from opposite side edges of the casing section 10 and the inner end wall of the casing section between each end of the semi-circular channel 17 and the side edge of the casing section is cut away as at 18 to provide a 30 passage for the conductor cord. A diagonally extending rib 12a is disposed adjacent each cut-away portion 18 and the inner end of the rib terminates in spaced relation to the longitudinal rib 12 to provide an air passage or vent 12b. 35

As shown in Figure 2, the contacts 14 are seated in the respective grooves 13 and the conductor cords 19 are anchored as at 20 to the respective contacts 14, the conductors respectively passing through the cut away portions 18 and being entirely separated from each other within the plug casing and at their points of passage from the casing and exterior thereof.

The resilient plug pulling device comprises a tubular coil spring 21 having a ring 22 at one end thereof removably received in the channel sections 17 to be locked in said sections when the casing sections are secured together. The other end of the tubular spring 21 is anchored in the pull handle 23 as shown in Figure 6 and said pull handle is provided with a cross head 24 outwardly of the tubular portion 25 to which the spring is anchored. The cross head 24 of the pull handle is of channel formation as shown in Figures 4 and 6 and the tubular portion 25 there- 55

of opens into the cross head to provide an unobstructed air passage from the interior of the plug casing to the tubular coil spring 21 and pull handle. A transverse opening 26 is formed in the channel shaped cross head 24 and the two conductor wires 19 may be brought together, passed through and anchored in the opening 26 and at a convenient point attached to a plug or other source of electrical energy.

10 From the above detailed description of the invention, it is believed that the construction and use thereof will at once be apparent, it being noted that the conductor wires are completely separated from each other within the plug casing, thereby eliminating the blowing of fuses and the burning of wires while a thorough ventilation of the plug is possible by directing the conductor wires from the plug casing exteriorly of the tubular resilient plug puller so that air may freely circulate through the plug puller into the plug casing. It is also to be understood that the resilient plug puller that is directly attached to the plug body relieves all strain on the conductor wires and liability of the wires being pulled loose 25 from the contacts is eliminated.

While there is herein shown and described the preferred embodiment of the invention, it is nevertheless to be understood that minor changes may be made therein without departing from the 30 spirit and scope of the invention as claimed.

I claim:—

1. In an electric contact plug of the character described, a plug body formed of sections having spacer ribs and ventilator openings therein, a pair of contacts therein, a tubular plug puller attached to one end thereof and including a coil 5 spring having one end anchored to the body and a transversely extending puller head at its outer end, the puller head having an opening extending transversely thereof, said plug puller being in open communication with the plug body to effect ventilation of the latter and conductor wires attached to the contacts and passing from the plug body in spaced relation to each other and at opposite sides of the plug puller and freely passing in juxtaposed relation through the transverse opening in the outer end of the puller head. 15

2. In an electric contact plug of the character described, a plug body, a pair of contacts therein, a tubular resilient plug puller attached to the plug body, conductor wires attached to the contacts, spaced from each other within the plug body and passing from the plug body respectively at opposite sides of the plug puller and the outer end of the plug puller having an opening therein through which the conductor wires are passed 20 with sufficient slack present in the conductor wires at opposite sides and exteriorly of the plug puller whereby strain on the wires is relieved during the pulling of the plug. 25
